UNITED STATES PATENT OFFICE.

FREDERIK NIELSEN, OF EPPING, NEAR SYDNEY, NEW SOUTH WALES, AUSTRALIA.

VULCANIZING RUBBER SOLES TO FABRIC OR OTHER UPPERS.

Application filed March 3, 1927, Serial No. 172,483, and in Australia March 17, 1926.

This invention relates to improvements in the process of vulcanizing rubber soles to fabric uppers and to apparatus for carrying same into effect.

- 5 In the manufacture heretofore of this class of boot or shoe, in which a flexible rubber bag has been employed on which the upper was mounted, it has presented an irregular shape, and, when placed in position 10 and the shoe mould closed, it was obscured from view. Consequently, any creases, which frequently occur, cannot be smoothed out by inflating the bag, and the raw rubber frequently extends beyond the sole top ridge 15 adhering to the sides of the upper leaving an unsightly appearance. Further, the shoe mould owing to the large surface and uneven distribution of metal not necessary for actual making of sole, loses considerable heat 20 by radiation.

The object of the present invention is to effect improvements in the manufacture of footwear of the aforementioned kind and is particularly directed to a method and means 25 whereby creases of the upper are obviated and disfigurement of the upper by rubber extruding beyond the sole ridge prevented.

According to my invention I attach fabric or other uppers to their insole by stitching, 30 riveting or the like leaving the toe and heel part open as the same cannot economically be stitched to make a close fit without creases.

By having the comparatively straight 35 sides of the shoe stitched or otherwise secured it makes the solutioning down of the curved toe and heel piece to the insole a simple matter. Besides, it ensures additional stability to the structure.

40 An important point at this stage of the process is that the shoe or boot is presented to the sole mould on the same last as that on which it was first mounted for lasting, thus eliminating unnecessary handling, and 45 preventing probable distortion of solutioned down part as well as soiling of the upper. The last is provided on its under surface with a diaphragm to which air or steam at a suitable temperature is admitted.

50 The air or steam entering the diagram at a suitable temperature, in addition to supplying pressure on the rubber while being vulcanized, also supplies heat for vulcanization.

After the assembled shoe has been positioned on the vulcanizing mould and locked,

air or steam is turned on and vulcanization takes place from inside of the shoe as well as from outside the sole and by so doing makes the upper and insole become inseparable from the sole rubber without in any way over-vulcanizing the base of the sole as is the case with some methods where the sole is vulcanized only from the base.

It will be seen that the vulcanization of the rubber from the inside is of utmost importance, not only because it hastens the process and makes it even from both sides, but because the perfect adhesion to the upper which is essential can only be effected with 70 thorough vulcanization. In the case of steam a higher pressure may be required in moulding some rubber compounds than is obtainable from the vulcanizer. To meet this demand the vulcanizer and diaphragm may be supplied direct from the one boiler, a reducing valve being inserted in the pipe leading to vulcanizer. Although the heat radiating from the diaphragm is reduced in 80 temperature by passing through a loose steel sole plate and also through the fabric insole, before coming in contact with the rubber, such a reduction is essential in the case of steam. If the reduction is found to be insufficient a further reduction may be obtained by having the loose steel sole plate made in two layers and a suitable piece of insulation material inserted between same. 85

The special purpose of the loose sole plate, furthermore, is to distribute an even pressure from the diaphragm to the extreme heel and toe part, where it is desired the sole shall adhere. 90

After vulcanization the steam or air inlet valve is shut off and the exhaust valve opened. Whereupon the diaphragm automatically conforms to its original dimensions.

With this process there is a minimum of handling resulting in reduced cost of production as the upper is not touched by hand from the time it is mounted on the last until it is removed as a finished article, consequently the very unsatisfactory method of solutioning the whole of the upper to the insole is obviated.

It is well known in the rubber trade that a satisfactory result cannot be obtained by vulcanizing from one side only, single side vulcanization being mostly suitable where the article is screwed to a base as in the case of rubber mats for motor cars and the like.

In order that my invention may be more readily understood reference will now be made to the accompanying drawings wherein

Figure 1 is a side elevation partly in section of my improved machine.

Figure 2 is a front view thereof partly in section with several parts removed.

Figure 3 is a plan of the sole moulds and Figure 4 is a section thereof on the line 10 4—4 of Figure 3.

Figure 5 is a side view of the moulds showing the operating means.

Figure 6 is a detail view on an enlarged scale of the outer bearings for the operating 15 shafts.

Figure 7 is an elevation partly in section of the last diaphragm and sole plate.

Figure 8 is a section on the line 8—8 of Figure 7.

20 Figure 9 is a plan of the sole plate.

Figure 10 is a detail view of the means provided for adjusting the vertical member to which the last supporting lever is pivoted.

Figure 11 is a plan showing the means 25 for hinging the last supporting lever.

Figure 12 is an elevation thereof.

Figure 13 is a section of the lever on the line 13—13 of Figure 12.

30 Figure 14 is a section on the line 14—14 of Figure 13.

The machine is provided with a frame 15 upon which the lower half of the vulcanizer is mounted. This vulcanizer consists of a lower or water chamber 16 and an upper portion or hot plate 17 upon which one or more 35 sets of moulds are mounted.

Ordinarily, the vulcanizer is supplied by steam from a boiler, but it may also be heated direct by gas and provision in such case may 40 be made for increasing the heating surface by corrugating the bottom of the vulcanizer. Heat insulating material may be placed round the vulcanizer to retain the heat.

45 A gauge glass safety valve and pressure gauge as well as means for supplying feed water are provided on the lower portion 16 which also has a pair of brackets or arms 18 for supporting the operating parts of the machine.

50 A vertical member 19 is pivoted to each bracket 18 and is adjustable in a vertical plane by a tie rod 20 which passes through an eye or lug 21, (see Figure 10,) bolted to the member 19, the tie rod being screwed 55 and provided with adjusting nuts on each side of the lug or eye.

To the vertical member 19 an arm 22 is pivoted. This arm supports the last and is formed at each end of I section material connected at the centre by cover plates 55 (see Figures 12 and 13). In the slot formed by the cover plates the extension 32 of the last is pivoted.

60 The arm 22 terminates at the pivot 56 and has a lug 57 (see Figure 14) upon which an

extension arm 58 is mounted concentrically with the pivot pin 56. Relative movement between the lever 22 and extension 58 is governed by a pin or stop 54 on the arm 22 engaging a shoulder 59 on the extension 70 arm 58.

A spring 24 connected to the extension arm 58 and to a slotted extension plate 61 of the bracket 18, raises the arm 22 and last 23 when the hinged lever or swing bolt 27 75 is removed from the end of the arm 22.

On pulling the cord 62 the arm 22 and last 23 are moved through part of a circle by an overhead lever 60 and cord 61 into a position at the rear of the machine where the 80 finished shoe is removed from the last and a fresh upper mounted thereon.

On again pulling the cord 62 the arm 22 is returned to its original position with the last above the mould but not in contact with 85 same. The foot lever 26 is now pressed with the result that the rod 25 raises the extension arm 58 against the action of the spring 24 and allows the last to enter the mould thereupon the hinged or swing bolt 27 is placed 90 in position on the arm 22 to secure it.

The hinged lever or swing bolt 27 on being placed on the arm 22 engages it at first lightly, but later on raising the handle the lever 27 exerts greater pressure between the last 95 and the mould. Adjustment of the hinged lever or swing bolt is effected by a sleeve 28 and right and left hand threads.

The last 23 is made of cast iron or the like and is hollowed out at its base to receive a strip of insulation 29, a metal or other diaphragm 30 and a steel insole 31. A cover plate 65 extends from the foot portion to the heel portion of the last. The hollowed out portion of the last extends to within a short distance of the toe piece where a narrow ridge is left to assist in keeping the toe part of the upper free from creasing.

The last has an extension 32 by which 110 it is pivoted in a balanced position to a horizontal member 22 and is given a parallel motion when leaving the mould by being connected by a link 33.

The last is further extended in a horizontal 115 direction in the form of an arm 34 to which the heel portion of the last is pivoted. This heel part has been detached from the last in order to make it possible for the finished shoe to be removed.

The heel portion of the last is provided with a combination lever consisting of one direct lever 35 attached to the level part and a second lever 36 which acts both as a locking and releasing lever. The heel lever 125 35 is kept constantly against the locking lever by means of a spring 37.

The diaphragm 30 is the same shape as the inner sole, but is somewhat shorter than the heel and toe pieces of the last as shown in

Figure 7, and consists of two sheets of metal, the lower of which is thicker than the upper, brazed together at their edges so as to form a space between them to which air or steam is admitted, inlet and discharge pipes 38-39 being provided to which suitable valves are connected.

The object of the last is to support the shoe or boot to act as a stay and oppose the upward pressure exerted by the diaphragm, and to carry the vulcanized shoe clear of the sole mould into a suitable position for the removal of the sole plate.

The last on rising from the mould is given a parallel motion derived from the link 33, one end of which contains an eccentric bearing 63 for adjustment, the other end having a roller which normally rests against a hook 64 on the end of the vertical member 19. The parallel motion continues until the fork shaped last arm 34 makes contact with the arm 22. The roller on the link 33 eventually engages a slot 40 on the opposite side of the pivot of the lever 19, and brings the last to a stop in a reversed position.

A sole plate 41 having flat extension pieces 42 is placed in the bottom of the mould. The extension pieces 42 serve to centralize the sole plate in the mould to protect its corners from damage when it is being replaced on hot plate, and to provide means for removing it from the finished shoe.

The moulds 43 rest on the hot plate and are built up in sets according to sizes of boots and shoes. To the mould plates proper (see Figure 8) a thin steel plate 44 is secured. This slightly over-hangs the edge of the mould plates and makes a close joint all round the upper and against the loose steel sole plate, and prevents the raw rubber entering on to the surface of the upper. Between the steel plate 44 and the guide plates 45 a sheet of insulating material 46 is placed. A sole plate 41 completes the bottom of the mould.

Each mould section is provided with racks 47 adapted to be engaged by pinions 48 mounted on shafts 49 and simultaneously operated by toothed quadrants 50 from a hand lever 51 pivoted to a bracket machine frame. A separate hand lever 51 is provided for each set of moulds and as many moulds as desired may be arranged side by side on one vulcanizer. The outer bearings for the shafts 49 are split (see Figure 6) so as to enable the moulds to be changed. A wedge or the like is provided between the shaft 49 and the moulds to ensure that the latter will make contact with the hot plate of the vulcanizer.

The hand levers 51 for operating the moulds are pivoted to a ratchet toothed bracket 52 secured to the machine frame. A bell crank extension of the lever 51 is con-

nected by an arm 53 to the toothed quadrant 50. A pawl 66 is provided for retaining the hand lever 51 in any desired position.

To enable the last 23 and horizontal member 22 to be rotated through part of a circle 70 without interfering with the supply pipes 38-39, a stuffing box 67 is mounted on the pivot pin 56 to which the air or steam is conducted through a hole in the pivot pin.

The uppers are made in the usual manner 75 and an insole is attached by sewing or rivets or the like. By this means the shape of the boot or shoe is practically determined before any solutioning down is applied. The toe and heel portions are left open for solutioning as this is the most practical and expeditious means of getting out the creases. Bearing in mind that the skirt portions of the upper, bent round on to the insole must be comparatively narrow so as to avoid 85 creases, the stitching or other means of securing the main part of the upper to the insole, overcomes a decided disability. By having it thus secured, the combined upper and insole may for all practical purposes 90 be considered one solid structure when vulcanizing the rubber sole on to the same.

The importance of this will be realized because with solutioning down processes of securing uppers there is a great liability of 95 the parts becoming detached especially where canvas is secured to canvas, as when the upper portion is wholly solutioned to the insole.

In operation a steel insole is first placed 100 in the combined upper and insole which are then mounted on the last after which the heel and toe portions are solutioned down. The sole surface having been prepared the mounted upper is now rotated through part 105 of a circle and positioned above its respective mould, being held in that position by the tensioning spring. By pressing the foot pedal the last and horizontal member descends on to the sole mould, the same having previously been closed and unvulcanized rubber placed therein. The lever or swing bolt is now brought into position and the handle raised. The exhaust valve from the diaphragm having been left open, the inlet 110 valve is slowly opened to admit steam. A few drops of water due to condensation will trickle out of the exhaust pipe and as soon as this stops, and steam is observed the exhaust valve is shut. After a predetermined 115 time the steam valve is shut off and the exhaust valve opened.

The mould is now opened by its operating lever and the hand lever removed from the horizontal lever supporting the last. 120 The horizontal lever and shoe now rise under the action of the spring: the sole plate is struck off and removed for cleaning. The overhead lever is now operated by its pull cord to bring the shoe to the reversed posi-

tion on the opposite side of the machine in order that it may be removed from the last after first operating the hand lever provided for contracting the heel portion of the last.

I claim:

1. A machine for constructing rubber soled boots or shoes having fabric uppers wherein the upper is under observation during the whole of the period of vulcanization, comprising a vulcanizer, mould plate mounted therein and bracket arms extending therefrom, a vertical member adjustably pivoted to said brackets, a hinged horizontal lever pivoted thereto adapted to pivotally support a last, an adjustable locking lever pivoted to said vulcanizer and adapted to secure the horizontal lever and last with respect to the mould, means for opening and closing said mould and operating means for said horizontal lever.

2. A machine for constructing rubber soled boots or shoes having fabric uppers wherein the upper is under observation during the whole of the period of vulcanization comprising a vulcanizer, a mould thereon said mould being divided centrally, and slideable on said vulcanizer by means of toothed quadrants and rack and pinion gear operated by a hand lever, a hinged horizontal lever carrying a last, said last having a foot portion and a heel portion movable with respect to each other, a cover plate between the heel and foot portion of the last, a recess in the base of said last, a strip of insulating material therein, a diaphragm beneath said insulation, inlet and outlet pipes connecting said diaphragm, and operating lever and a locking lever for said heel portions.

3. In a machine for constructing rubber soled boots or shoes having fabric uppers wherein the upper is under observation during the whole of the period of vulcaniza-

tion, a mould divided centrally and slideable on a vulcanizing hot plate by means of quadrant rack and pinion gear, said mould being built up of a mould plate proper which rests on the hot plate, a thin steel plate which projects slightly over the inner edge of the mould plate, a sheet of insulation material above said steel plate, and a guide plate, said guide plate being provided with a wedge or the like which engages the operating shaft and forces the mould into contact with the hot plate, the mould being completed by a sole plate.

4. In a machine for constructing rubber soled boots or shoes having fabric uppers wherein the upper is under observation during the whole of the vulcanizing period, a hinged lever adapted to support a last, said hinged lever being adapted to be rotated through an angle of approximately 180° and whose movement is such that at first the last rises from the mould with a parallel motion.

5. In a machine for constructing rubber soled boots or shoes having fabric uppers wherein the upper is under observation during the whole of the vulcanizing period, a hinged lever adapted to support a last, said hinged lever having an extension concentrically pivoted with the main lever and connected by a spring to a pivoted and slotted extension of the vulcanizer bracket and adapted to be raised by a foot lever, said hinged lever being provided with means for operating and locking the heel portion of the last, said last being pivoted to the hinged lever and having an extension eccentrically connected to a link whose opposite end normally rests against a hook on the end of the member to which the hinged lever is pivoted.

In testimony whereof I have hereunto set my hand.

FREDERIK NIELSEN.
